UNITED STATES PATENT OFFICE.

HEZEKIAH ELLIS DEPP, OF SEDALIA, MISSOURI.

STEAM AND AIR ENGINE.

SPECIFICATION forming part of Letters Patent No. 290,405, dated December 18, 1883.

Application filed October 2, 1883. (No model.)

To all whom it may concern:

Be it known that I, HEZEKIAH E. DEPP, a citizen of the United States, residing at Sedalia, in the county of Pettis and State of Missouri, have invented a new and Improved 5 Steam and Air Engine, of which the following, in connection with the annexed drawings, is a specification.

My invention relates to improvements in 10 that class of engines which are driven by means of steam and compressed air combined, and the object is to improve the construction and efficiency of the engine patented to me in the United States April 25, 1882, and numbered 15 256,826, and to utilize the exhaust products from the main engine and the compressing-engine for heating the air delivered from the compressing-cylinders, as well as the lubricating-water of the air-compressors and the feed-water for the boilers, and delivering said 20 heated air to the boiler to be mixed with the steam generated therein, and thereby saving heat, improving the effectiveness of the motive agent, and avoiding waste of water.

To this end my invention consists, first, in an improved method of operating engines, consisting in admitting steam from the boiler into the compressor-engine cylinder, then exhausting it into the main-engine cylinder, and 25 admitting additional steam into said cylinder, then exhausting the combined steam and air into a casing, jacket, or pipe surrounding the pipes containing compressed air and the pipe containing the feed-water, or pipes containing 30 the feed-water and waste lubricating-water from the compressing-cylinders, and by said combined air and steam exhaust of the compressing-engine, or both the compressing-engine and the main engine heating the compressed air delivered from the compressing cylinder or cylinders and the feed-water, or 35 both the feed-water and the lubricating-water on their passage to the boiler, and in this heated state mingling the compressed air, feed-water of the "doctor," or both said feed-water and the lubricating-water of the compressing cylinder or cylinders, with the body 40 of steam and water within the boiler, as hereinafter specified; and it consists, second, in 45 certain novel combinations of devices, as hereinafter described and specifically claimed,

whereby an improved compressed-air and steam engine or apparatus is produced, where-in the heat from the exhaust products are utilized for the purpose of heating the compressed air, the feed-water, and the lubricating-water of the compressor or compressors during the delivery of the same to the boiler. 55

Figure 1 represents a side elevation, partly in section, of the apparatus for carrying out 60 my invention; and Figs. 2, 3, and 4 are enlarged cross-sections of the air and feed pipes incased in a jacket or exhaust-pipe of main engine.

In the drawings, A represents a boiler of 65 any suitable size and construction, and B is the main engine, having the usual fly-wheel and operating parts.

The air-compressor consists of a steam-cylinder, C, and one or more air-cylinders, D 7c and E, of the ordinary construction. The compressing-engine C receives steam through the pipe a, connected to the boiler by opening the valve a', and the steam is exhausted through the pipe d into the cylinder of the main engine B by opening the valve e and closing a valve or cock, e', in pipe k. After this engine is started, steam and compressed air combined are admitted through pipe b on opening the valve e, if required. The exhaust products of the 80 air-compressing steam-cylinder C, by closing valve e and opening a valve or cock, e', in pipe k, pass through pipe k, while the exhaust from the main engine B passes through pipe i into an enlarged casing, jacket, or pipe, F, within 85 which are arranged the delivery pipe or pipes k' of the air-cylinders—one or more—as well as the feed-water pipe g, leading from the feed-pump G to the boiler, and the pipe h³ for the water used for lubricating the air-cylinder. 90 By means of the heat from the exhaust products of the compressor-engine C, or both this engine and the main engine B, together with the heat caused by the compression of the air and the friction of the pipes and valves, 95 which enter said casing, jacket, or pipe, the air and feed-water will be heated while passing through the small pipe h' or pipes g' h' h², leading to the boiler.

The said casing, jacket, or pipe may be 100 made of a size suitable for containing either one pipe, as shown in Fig. 1, or two, three, or

more pipes for air and water, (see Figs. 2, 3, and 4 of the drawings;) and, if desired, it may be incased with a non-conducting covering, to prevent radiation of heat. The heated air 5 will be conducted to the steam-space of the boiler, to be mixed with the steam, while the heated water may either be conveyed into said space or into the water-space, as found most desirable. After heating the air and feed 10 pipe or pipes, the exhaust in casing, jacket, or pipe F may escape into the atmosphere at h^2 , or otherwise suitably.

By my invention as represented and herein-described, I dispense with the use of the reservoir shown in my aforesaid patent, and also utilize the heat of the exhaust products for heating the water of the boiler; also, the waste water for supplying the boiler. The heat caused by the exhaust products and the compression and friction of the air is partly absorbed by the water, and it thus enters the boiler along with the air in a heated state, while the air heated by exhaust-steam and mechanically heated, itself serves for heating the 25 water in the boiler. The air and water may only be subjected to the exhaust-heat from the compressing-engine C, before passing into the boiler, by closing the right-hand end of the pipe F against the exhaust-pipe i; or they may 30 be subjected to the heat of the exhaust from both the compressing-engine C and the main engine B by having the right-hand end of pipe F open and the pipe i arranged to exhaust into it, as shown in the drawings, or in 35 any other suitable manner, thereby utilizing the additional heat of said exhaust.

The utilization of the heat herein referred to is realized in the boiler either by an enlivening of the steam and preventing rapid 40 condensation, or by acting as an auxiliary heating means, or by combination of both these effects upon the steam and water in the boiler.

The different parts or pipes may be provided 45 with such cocks, regulation, or governing devices as are commonly used in engines for like purposes, additional to those represented, as circumstances may require, without departing from my invention.

50 It will be understood that the air-pipes h h' and waste-water pipe h^3 and the water-pipe g will unite into one common feed or supply pipe leading into the boiler, and that thus the power of the compressing air-cylinders and 55 the water-pump G can be utilized for forcing the same into the boiler; and, further, that when the compressing apparatus is set higher than the water-line of the boiler the waste lubricating-water will more readily flow into the 60 boiler.

The operation is as follows: Steam being generated to the desired pressure in the boiler, (all the valves being closed,) the valve a' in pipe a, leading to the steam-cylinder C, is 65 opened, and thereby live steam is admitted to the cylinder from the boiler, and in a short

time afterward the main engine B is started by admitting the exhaust from cylinder C to the cylinder of the main engine B. If the motive power for the main engine is not sufficient, 70 the valve c in the pipe b is opened and additional steam is admitted from the boiler. In practice, said valve will be connected with and operated by the governor of engine B. The amount of steam and compressed air is 75 proportioned in such manner as to regulate the exhaust from the main engine. The exhaust from the engine-cylinder of the compressing-engine C, as also that from the main engine B, will, after a proper closing of valve 80 or cock e and opening of a valve or cock, e', in pipe k, be conveyed into the jacket, casing, or pipe F, in which are arranged the delivery-pipes from the air-cylinders and the lubricating apparatus of said cylinders, and also the 85 feed-water pipe of the boiler, and it serves to heat the air and water before delivery of the same to the boiler, the air by this means being caused to increase its volume, while the feed-water in its pipe is heated before entering the 90 water or steam space of the boiler, and thus is in a condition for aiding in and facilitating the generation of steam. The thus mixed or combined steam and compressed air, after the first few strokes of the engine, forms the motive 95 agent for operating the engines.

It will be readily understood that the original steam-pressure, which would be reduced by operating the air-compressor to about one-fourth, will in a great degree be compensated 100 for in volume by means of the compressed air introduced into the boiler after being heated on its way to the boiler by exhaust-steam, so that there will be but very little loss of pressure and naturally of power.

105 In the drawings I have not shown the cylinders E and D as provided with the usual valves required upon the same; but it will be understood that these cylinders are to be provided with such valves, as well as all the well-known appliances commonly used in connection with such cylinders; also, that these cylinders are to be provided with the suitable usual means for lubricating them with water, and that the water used to lubricate the air cylinder or cylinders may also be conveyed through a delivery pipe or pipes, h^3 , to the boiler, and such water being heated by means of compression in said cylinder or cylinders and the exhaust products, will greatly aid the combined steam and compressed-air apparatus by reducing the quantity of feed-water required to be supplied to the boiler from the feed-pump G.

115 I am aware that exhaust-steam has been 120 before used for heating feed-water on its passage to the boiler; but I am not aware that a combined air and steam engine has been organized so as to have its compressed air and the feed-water or the feed-water and lubricating-water heated within an inclosing-jacket, casing, or pipe by the exhaust-steam of the 125 130

compressing-engine, or by both the exhaust-steam of the compressing-engine and of the main engine, and said air and water in their heated condition introduced into the boiler, 5 as I have described and shown.

What I claim as my invention, and desire to secure by Letters Patent, is—

1. The method of operating engines herein described, consisting in admitting steam from 10 the boiler into the compressor-engine cylinder, then exhausting it into the main-engine cylinder, and admitting additional steam into said cylinder, then exhausting the combined steam and air into a casing, jacket, or pipe 15 surrounding the compressed-air pipes and the water-pipes, and by said combined air and steam-exhaust heating the compressed air and the water in the pipes on their way to the boiler, and in this heated condition mingling 20 the compressed air from the compressing cylinder or cylinders and the said water with the body of steam and water within the boiler, substantially as specified.

2. The combination of a boiler, A, and steam- 25 engine B, an air-compressing engine, C D E, suitable inlet-pipes, and the delivery-pipes inclosed in a casing, jacket, or pipe containing the exhaust products of the main and compressing engines, substantially as and for the 30 purpose set forth.

3. The combination of a boiler, A, and steam- engine B, an air-compressing engine, C D E,

pipes a b d, having suitable valves, and a feed-water pipe, g, substantially as and for the purpose described.

4. In an engine operated by combined steam and compressed air, the method herein described of utilizing combined exhaust-steam and air from the compressing-engine or both the compressing and main engines, consisting 40 in introducing said combined exhaust-steam and air into a casing, jacket, or pipe containing the compressed-air-delivery pipes of the compressing cylinder or cylinders and the feed-water pipe, or both the feed-water and 45 the lubricating-water pipes, and heating the said compressed air and said water on their way to the boiler, introducing the same into the boiler, and mingling them with the steam and water therein, substantially as described. 50

5. The combination of a boiler, A, a main engine, B, a compressing-engine, C, provided with one or more air-cylinders with inlet-pipes having suitable valves and with outlet-pipes for the air, a feed-water pipe, and a casing, jacket, or pipe, F, in which the outlet air pipe or pipes and the water-pipes are inclosed, and the exhaust from the main and compressing engines is introduced, substantially as and for the purpose specified. 55
